United States Patent

Des. 234,441
Patented Mar. 4, 1975

234,441

PHOTOFASH UNIT

John De Filippis, South Amboy, and Robert L. Taylor,
Imlaytown, N.J., assignors to International Telephone
and Telegraph Corporation, Nutley, N.J.

Filed May 21, 1973, Ser. No. 362,038

Term of patent 14 years

Int. Cl. D16—05

U.S. Cl. D61—1 F

FIG. 1 is a left front perspective view of a photoflash unit showing our new design;

FIG. 2 is a right side elevational view thereof;

FIG. 3 is a rear elevational view thereof; and

FIG. 4 is a top plan view thereof.

We claim:

The ornamental design for a photoflash unit, substantially as shown and described.
